DUPLEX CIGAR TRANSFER

Joseph A. Neumair, Hollis, N. Y., assignor to
International Cigar Machinery Company, a
corporation of New Jersey

Application September 29, 1934, Serial No. 746,233

18 Claims. (Cl. 131—61)

This invention relates to automatic cigar transfer mechanism, its main object being to transfer a cigar from a cigar enveloping machine to a cigar banding mechanism, and at the same time 5 turn the cigar 180 degrees about its transverse axis to reverse the cigar end for end so that it will be in the proper position to be banded when it arrives at band-applying position.

A further object is to provide a duplex cigar 10 transfer having a novel construction and mode of operation and designed to carry the reversed cigar to band-applying position and move it away from said position after it is banded. For this purpose the duplex cigar transfer comprises a 15 pair of reciprocable slides having movements of equal amplitude and at the same speed, and each provided with a set of clamping fingers which are moved into a position astride the reversed cigar and the cigar at band-applying position, respectively, to clamp the sides of the cigars. The first 20 set of fingers delivers the reversed cigar to band-applying position where it is gripped by the second set of fingers after being banded, and transferred to delivery position.

25 In the process of enveloping and banding cigars it is essential to keep them in the same right side up position as they were selected; accordingly, a further object is to prevent them from being turned circumferentially while taken from one 30 position to another, especially when the banding mechanism is so located that the cigar must be swung about its transverse axis in order to apply the band to the right part of the cigar.

These objects in the present invention are 35 achieved by employing a set of grippers which receive the cigar from the enveloping machine and swing it 180 degrees about its transverse axis. Thereupon the first set of clamping fingers of the duplex cigar transfer takes the cigar and 40 delivers it to the banding mechanism, holding it until the bander head has descended onto the cigar and the folding fingers have engaged the band and folded the same partly around the cigar. The folding fingers thus hold the cigar 45 while the clamping fingers are released and moved back to take the next cigar from the grippers. The banded cigar is then gripped by the second set of clamping fingers and transferred to delivery position.

50 With these and other objects not specifically mentioned in view, the invention consists in certain constructions and combinations hereinafter fully described and then specifically set forth in the claims hereunto appended.

55 In the accompanying drawings which form a

part of this specification and in which like characters of reference indicate the same or like parts:

Fig. 1 is a side view of the complete cigar transfer mechanism;

Fig. 2 is a plan view of Fig. 1 showing the grippers for reversing the cigar end for end, and the duplex cigar transfer and its operating mechanism, which removes the cigar from the grippers and advances it to the banding machine;

Fig. 3 is a sectional end elevation of Fig. 1; and 10

Fig. 4 is a detail view showing the cigar being held by the bander fingers of the banding mechanism.

In carrying the invention into effect there is provided a device for gripping a cigar, mechanism for turning said device one-half turn to reverse the gripped cigar end for end, means for clamping the sides of the reversed cigar and removing it from said device and depositing it in band-applying position, and mechanism operating in synchronism with said means for clamping the sides of the cigar deposited at band-applying position and transferring it away from said position. In the best constructions contemplated there is provided a duplex transfer 25 comprising a pair of reciprocable pivoted heads, a set of clamping fingers on each of said heads to engage the cigar reversed by said device and the cigar at band-applying position, respectively, and transfer them to band-applying and delivery 30 positions, respectively. These various means and parts may be widely varied in construction for the particular arrangement selected to illustrate the invention is but one of many possible concrete embodiments of the same. The invention, 35 therefore, is not to be restricted to the specific construction shown and described.

The cigar transfer mechanism is operated from the main drive of a cigar enveloping machine such as disclosed in the patent to H. H. Wheeler, 40 1,899,174, issued February 23, 1933, by means of a chain 10 driving a sprocket 11 actuating the cam shaft 12 (Figs. 1 and 2). The enveloped cigars C ejected from the turret T of said enveloping machine are delivered to the transfer 45 mechanism by means of swingable transfer arms 13 and 14 forming a part of the enveloping machine. Arms 13 are fixedly mounted on a shaft 15 journaled in bearings of the side frames of the enveloping machine (not shown) and provided with pockets on their free ends to receive the cigar as it is ejected from the turret T, as shown in dotted lines in Fig. 1. Shaft 15 is suitably oscillated from the enveloping machine. The arms 14 are actuated by means of a plate 55

cam 16 operating a connecting rod 17 through a cam lever 18 having a follower engaging the cam track in one face of cam 16, the upper end of rod 17 being connected to one arm of bell crank lever 19 and the other arm of lever 19 carrying a flanged stud which engages the hooked end 21 of a lever 22 connected to a lug 23 on one of the arms 14. When the arms 13 are swung downwardly they deliver the cigars C onto a table 24 and enter suitable slots provided in the table to receive them. The arms 14 are fixed on a sleeve 25 loose on shaft 15 and having a circumferential slot receiving the screw which secures the hub of the arms 13 to the shaft 15, one of the arms 14 as heretofore described being equipped with a lever 22, thereby actuating both arms 14 in unison.

The bed 104, of the enveloping machine carries angle brackets 105, which support each of the side frames 26 and 27 (Fig. 1). The table 24, of the transfer unit is attached to projecting arms of the side frames 106 and 107, of the enveloping machine (Fig. 3).

After the cigar C is delivered onto the table 24, which is supported by the side frames 26 and 27 of the transfer unit, arms 13 move down through the slots in the table 24 out of engagement with the cigar while arms 14 rest on the cigar and prevent the same from turning circumferentially. A hook-shaped pusher 28 then moves the cigar from beneath arms 14 and inserts it between the grippers 29 and 30. Pusher 28 is fastened to a rack 31 sliding in a track provided in the bracket 32 attached to the table 24. The rack 31 is actuated by a gear segment 33 having a projecting arm 34 pivotally connected to one end of a rod 35, the other end of rod 35 being connected to a cam lever 36 provided with a follower engaging the cam track in the other face of cam 16. The lever 36 is fulcrumed on the cam lever shaft 37 supported in bearings of the side frames 36 and 27. Gripper 39 is pivotally mounted on a pin 38 extending transversely of gripper 30 forming therewith a pocket in which the cigar C is inserted by pusher 28. Gripper 29 is held firmly against the cigar C in the pocket so formed by the action of a compression spring 39 coiled about a stop pin connecting the grippers 29 and 30. The latter is provided with adjustable flanges forming the end wall of the pocket and is clamped to a sleeve 30a loosely mounted on the stationary vertical shaft 40, the grippers being oscillated about a vertical axis by means of a gear sector 41 fixed on sleeve 30a and meshing with a stationary rack 42 fastened to the table 24 (Fig. 2). Vertical shaft 40 is fixed in a slide 43 (Figs. 1 and 2), reciprocable in a slideway provided in the table 24. To the bottom of slide 43 is fastened a block 44 connected by a link 45 to an arm 46 which is oscillated from a double arm cam lever 47 by means of a connecting rod 48, the lever 47 carrying a roller 49 engaging a cam track of cam 50 mounted on cam shaft 42, and cam lever 47 being fulcrumed on shaft 37 and the arm 46 being fulcrumed on shaft 51 supported by side frames 26 and 27. During the forward motion of slide 43, imparted thereto from cam lever 47, gear sector 41 is rotated one half-turn by the stationary rack 42, causing the grippers 29 and 30 to turn therewith and thereby swing the cigar 180 degrees around its transverse axis without turning the cigar circumferentially. A coil spring 40a wound about the sleeve 30a on shaft 40, has one end anchored in the gripper 30 and its other end is

held in a collar 40b fastened to shaft 40. The spring 40a causes the grippers 29 and 30 to turn with the shaft 40 and eliminates any backlash between gear sector 41 and rack 42. The cigar in this manner is carried from its position shown in Fig. 1 to a position shown in Fig. 2. In being swung the cigar is turned end for end so that it will be in the proper position to be banded when it arrives at the band-applying position.

The cigar C is then removed from the pocket 10 formed by grippers 29 and 30 by means of the first pair of clamping fingers 60 and 61 of the duplex cigar transfer, operated by mechanism which will be presently described, which take the cigar to the banding station and hold the same during the initial stages of the banding operation. When the clamping fingers have engaged the cigar, the pivoted gripper 29 is released from the cigar by means of a stop screw 52 carried by one arm of a forked lever 53 in position to engage and depress the lug of gripper 29 and thus compress the spring 39. A similar screw 52a in the other arm of lever 53 engages an opposite lug of the gripper 29, thereby opening the same to admit the cigar advanced on table 24 by the pusher 28, the cigar having previously been deposited on table 24 by the transfer arms 13 and 14. The lever 53 is fulcrumed on a stud 52 supported in a bracket 55 attached to table 24, lever 53 being actuated by a rod 56 connected to a cam lever 57 fulcrumed on shaft 37, said cam lever being provided with a roller 58 fitting a cam track of cam 59.

As soon as the cigar C has been removed from the pocket formed by grippers 29 and 30, the latter return to their original position and stand ready to receive another cigar. The clamping fingers 60 and 61 are attached to arms 62 pivoted to a supporting head 63, each arm 62 being equipped with a roller 64 held by means of a tension spring 65 against a wedge-shaped member 66 (Figs. 2 and 3), member 66 controlling the opening and closing of the pocket formed by fingers 60 and 61. The wedge 66 is fastened to a slide rod 67, a portion of which has rack teeth 45 meshing with a gear segment 68 of arm 69, Fig. 3, arm 69 being equipped with a roller 70 engaging the bottom of a cam rail 71. The latter is supported from its ends by brackets 72 and 73 (Fig. 2) fixed on shaft 74 which is journaled in bearings 75 carried by the table 24. An arm 76 projecting from bracket 73 is connected by a rod 77 (Fig. 2), to one arm 78 of a double arm cam lever 79 actuated by means of a roller 80 on its other arm from a plate cam 81. The action of cam 81 through rod 77 operates the rail 71, the descent of rail 71 engaging the roller 70 of arm 69 which is pivoted on shaft 74 and causing the segment 68 to move slide rod 67 outwardly, thus opening the fingers 60 and 61; the outward movement of rod 67 compressing the spring 82 thereon. When the rail 71 ascends, the spring 82 expands and returns the wedge 66 to its original position, thus closing the fingers 60 and 61. While the arms 62 are spread apart during the descent of cam rail 71 they are swung downwardly to bring the clamp fingers 60 and 61 into a position astride the cigar held between the grippers 29 and 30 after the same has been reversed end for end. For this purpose the cam 50 is provided with a cam groove receiving a roller 83 of a double arm cam lever 84, the arm 85 of lever 84 operating a rod 86 connected to shaft 87. Arms 88 loose on shaft 87 have their other ends pivoted on shaft 74 and the head 63 75

is slidably mounted on shafts 74 and 81, whereby downward movement of the rod 86 will swing the head 63 downwardly on shaft 74 to bring the separated fingers 60 and 61 into a position astride the cigar. When the fingers 60 and 61 reach this position they are closed on the cigar so that they will remove the same from the grippers 29 and 30 during the transverse movement of head 63 on shafts 74 and 81. To assure the removal of the cigar the finger 60 is of sufficient length to engage the mid-section of the cigar, the finger 63 having a notch in its bottom fitting the underlying arm of the gripper 29 to permit the finger 60 to straddle the same in order that the full length of the finger may engage the cigar. The transverse movement of the head 63 is controlled by means of a horizontal slide 89 which is guided in slide blocks 90 suspended from the table 24. Slide 89 receives reciprocating motion through a gear segment 91 of arm 92, segment 91 meshing with the rack teeth provided on the slide 89. Slide 89 is actuated by cam 81 having a cam groove receiving roller 93 on one arm of the double cam lever 94, the arm 95 of lever 94 carrying a rod 96 connected to the arm 92. The slide 89 is provided with slotted blocks 97 engaging rollers 98 carried by the arms 99 of the heads 63 and 100; in this manner a back and forth motion is transmitted to the heads 63 and 100. Since the construction of the head 100 on which the second pair of clamping fingers 101 and 102 of the duplex cigar transfer is carried, is similar to the head 63, like characters of reference are used to designate corresponding parts, and the description thereof need not be repeated herein.

The operation of the novel transfer is as follows:

The enveloped cigar ejected from the turret T is deposited on the table 24 by the transfer arms 13 and 14 and then inserted between the grippers 29 and 30 by the pusher 28. After the cigar has been swung 180 degrees by the grippers 29 and 30, clamping fingers 60 and 61 descend and clamp the cigar and slide it sidewise to the band-applying position under the banding mechanism M of conventional construction, (Fig. 2), where the cigar is held between the fingers 60, 61 until the bander head H descends and presses the band against the cigar, whereupon the band folding fingers F swing inward, folding the band partly around the cigar as shown in Fig. 4. While the cigar is thus held by fingers F the clamping fingers 60, 61 are released when the rail 71 moves downwardly into engagement with the rollers 70. The clamping fingers 60, 61 then rise and move back to their starting position, the bottom folding fingers K in the meantime having moved in and completely folded the band B around the cigar. The fingers 60, 61 and 101, 102 then descend, the former pair engaging the cigar now held by the grippers 29, 30 and the latter pair engage the banded cigar previously delivered to the banding mechanism. The heads 63 and 100 then move forward, the fingers 60 and 61 of the former sliding the cigar to the bander and the fingers 101 and 102 of the latter sliding the banded cigar from the bander to delivery position in which a pusher 103 on head 100 propels the banded cigar previously deposited by the clamping fingers of head 100 onto the delivery end of table 24. It will be observed that during the entire operation of the novel cigar transfer mechanism, the cigar is held firmly and in the right side up position so that the banded

cigars can be repacked in the same box from which they were taken.

What is claimed is:

1. The combination with a device for gripping a cigar, of mechanism for turning said device one half-turn to reverse the gripped cigar end for end, oscillating means for clamping the reversed cigar while it is held by said device and removing the cigar therefrom and depositing it in band-applying position, and oscillating mechanism operating in synchronism with said means for clamping the cigar deposited at band-applying position after it has been released by said means and transferring it away from said position. 5

2. The combination with a device for gripping a cigar, of mechanism for turning said device one half-turn to reverse the gripped cigar end for end, means for clamping the reversed cigar while it is held by said device and removing the cigar therefrom and depositing it in band-applying position, mechanism operating in synchronism with said means for clamping the cigar deposited at band-applying position after it has been released by said means and transferring it away from said position, and mechanism for releasing the reversed cigar in said device after it has been clamped by said means. 20

3. The combination with a device for gripping a cigar, of mechanism for turning said device one half-turn to reverse the gripped cigar end for end, means for clamping the reversed cigar while it is held by said device and removing the cigar therefrom and depositing it in band-applying position, and mechanism operating in synchronism with said means for clamping the cigar deposited at band-applying position after it has been released by said means and transferring it away from said position, said device including a reciprocable slide, an upright shaft fixed in said slide, a stationary gripper loosely mounted on said shaft, and a movable gripper pivoted on said stationary gripper, and said mechanism including a spring having its ends fixedly connected to said shaft and stationary gripper, a gear sector fixedly connected to said stationary gripper, and a stationary rack meshing with said gear sector to turn said grippers one half-turn during each stroke of said slide. 30

4. The combination with a device for gripping a cigar, of mechanism for turning said device one half-turn to reverse the gripped cigar end for end, means for clamping the reversed cigar while it is held by said device and removing the cigar therefrom and depositing it in band-applying position, and mechanism operating in synchronism with said means for clamping the cigar deposited at band-applying position after it has been released by said means and transferring it away from said position, said means including a reciprocable head, a pair of clamping fingers pivoted on said head, a wedge-shaped block engaging said fingers, a spring connecting said fingers and pressing them against said block, and mechanism for actuating said block to cause said fingers to clamp the reversed cigar in said device and transfer it to band-applying position and release it in said position. 50

5. The combination with a device for gripping a cigar, of mechanism for turning said device one half-turn to reverse the gripped cigar end for end, means for clamping the reversed cigar while it is held by said device and removing the cigar therefrom and depositing it in band-applying position, and mechanism operating in synchronism 70

with said means for clamping the cigar deposited at band-applying position after it has been released by said means and transferring it away from said position, said mechanism including a 5 reciprocable head, a pair of clamping fingers pivoted on said head, a wedge-shaped block engaging said fingers, a spring connecting said fingers and pressing them against said block, means for actuating said block to cause said fingers to clamp 10 the cigar deposited in band-applying position and advance it sidewise to delivery position and release it in delivery position and a pusher on said head arranged to engage and further advance the cigar previously deposited in delivery position by 15 said clamping fingers.

6. The combination with a device for gripping a cigar, of mechanism for turning said device one-half turn to reverse the gripped cigar end for end, means for clamping the reversed cigar while 20 it is held by said device and removing the cigar therefrom and depositing it in band-applying position, mechanism operating in synchronism with said means for clamping the cigar deposited at band-applying position after it has been released by said means and transferring it away from said position, mechanism for releasing the reversed cigar in said device after it has been clamped by said means, said device including a reciprocable slide, a stationary gripper mounted 25 on said slide, and a spring-pressed gripper pivoted on said stationary gripper, and said releasing mechanism including a cam-operated lever arranged to strike said spring-pressed gripper and disengage it from the reversed cigar.

7. The combination with a device for gripping a cigar, of mechanism for turning said device one half-turn to reverse the gripped cigar end for end, oscillating means for clamping the sides of 30 the reversed cigar and removing it from said device and depositing it in band-applying position, and oscillating mechanism operating in synchronism with said means for clamping the sides of the cigar deposited at band-applying position and transferring it away from said position.

8. The combination with a device for gripping a cigar, of mechanism for turning said device one half-turn to reverse the gripped cigar end for end, means for clamping the sides of the reversed cigar and removing it from said device and 35 depositing it in band-applying position, mechanism operating in synchronism with said means for clamping the sides of the cigar deposited at band-applying position and transferring it away from said position, said means including a reciprocable pivoted head, a pair of clamping fingers pivotally mounted on said head, a wedge-shaped block engaging said fingers, a spring connecting said fingers and pressing them against said block, mechanism for reciprocating said head and 40 swinging it up and down on its pivot, to disengage said fingers from the cigar at band-applying position and move them to a position astride the reversed cigar, and mechanism for actuating said block to cause said fingers to clamp the reversed cigar in said device and carry it to band-applying position and release it in said position.

9. The combination with a device for gripping a cigar, of mechanism for turning said device one half-turn to reverse the gripped cigar end for 45 end, means for clamping the sides of the reversed cigar and removing it from said device and depositing it in band-applying position, mechanism operating in synchronism with said means for clamping the sides of the cigar deposited at band-applying position and transferring it away from said position, said means including a reciprocable pivoted head, a pair of clamping fingers fulcrumed on said head, a 50

ferring it away from said position, said mechanism including a reciprocable pivoted head, a pair of clamping fingers fulcrumed on said head, a wedge-shaped block engaging said fingers, a spring connecting said fingers and pressing them against said block, means for reciprocating said head and swinging it up and down on its pivot to disengage said fingers from the cigar at delivery position and move them to a position astride the cigar at band-applying position, 55 means for actuating said block to cause said fingers to clamp the cigar deposited in band-applying position and carry it to delivery position and release it in delivery position, and a pusher on said head arranged to engage and further advance the cigar previously deposited in delivery position by said clamping fingers.

10. The combination with a device for gripping a cigar, of mechanism for turning said device one half-turn to reverse the cigar end for 20 end, and means for clamping the reversed cigar while it is held by said device and removing the cigar therefrom and depositing it in band-applying position, said means including a reciprocable head, a pair of clamping fingers fulcrumed on 25 said head, a wedge-shaped block engaging said fingers, a spring connecting said fingers and pressing them against said block, and mechanism for actuating said block to cause said fingers to clamp the reversed cigar in said device and transfer it to band-applying position and release it in said position.

11. The combination with a device for gripping a cigar, of mechanism for turning said device one half-turn to reverse the gripped cigar end 35 for end, and mechanism for releasing the gripped cigar in said device after it has been reversed, said device including a reciprocable slide, a stationary gripper mounted on said slide, and a spring-pressed gripper pivoted on said stationary 40 gripper, and said releasing mechanism including a cam-operated lever arranged to strike said spring-pressed gripper and disengage it from the reversed cigar.

12. The combination with a device for gripping a cigar, of mechanism for turning said device one half-turn to reverse the gripped cigar end for end, said device including a reciprocable slide, an upright shaft fixed in said slide, a stationary gripper loosely mounted on said shaft, 50 and a movable gripper pivoted on said stationary gripper, and said mechanism including a spring having its end fixedly connected to said shaft and stationary gripper, a gear sector fixedly connected to said stationary gripper, and a stationary rack meshing with said gear sector to turn said grippers one half-turn during each stroke of said slide.

13. The combination with oscillating means for clamping the sides of a cigar and carrying it to 60 band-playing position and depositing it in said position, of oscillating mechanism operating in synchronism with said means for clamping the sides of the cigar deposited at band-applying position and transferring it away from said position.

14. The combination with means for clamping the sides of a cigar and carrying it to band-playing position and depositing it in said position, of mechanism operating in synchronism with said 70 means for clamping the sides of the cigar deposited at band-applying position and transferring it away from said position, said means including a reciprocable pivoted head, a pair of clamping fingers fulcrumed on said head, a 75

wedge-shaped block engaging said fingers, a spring connecting said fingers and pressing them against said block, mechanism for reciprocating said head and swinging it up and down on its pivot to disengage said fingers from the cigar at band-applying position and move them to a position astride a cigar, and mechanism for actuating said block to cause said fingers to clamp a cigar and carry it to band-applying position and release it in said position.

15. The combination with means for clamping the sides of a cigar and carrying it to band-applying position and depositing it in said position, of mechanism operating in synchronism with said means for clamping the sides of the cigar deposited at band-applying position and transferring it away from said position, said mechanism including a reciprocable pivoted head, a pair of clamping fingers fulcrumed on said head, a wedge-shaped block engaging said fingers, a spring connecting said fingers and pressing them against said block, means for reciprocating said head and swinging it up and down on its pivot, to disengage said fingers from the cigar at delivery position and move them to a position astride the cigar at band-applying position, means for actuating said block to cause said fingers to clamp the cigar deposited in band-applying position and carry it to delivery position, and a pusher on said head arranged to engage and further advance the cigar previously deposited in delivery position by said clamping fingers.

16. Means for clamping the sides of a cigar and carrying it to band-playing position and depositing it in said position, comprising a reciprocable pivoted head, a pair of clamping fingers fulcrumed on said head, a wedge-shaped block engaging said fingers, a spring connecting said

fingers and pressing them against said block, mechanism for reciprocating said head and swinging it up and down on its pivot, to disengage said fingers from the cigar at band-applying position and move them to a position astride a cigar, and mechanism for actuating said block to cause said fingers to clamp a cigar and carry it to band-applying position and release it in said position.

17. Mechanism for clamping the sides of a cigar at band-applying position and transferring it away from said position comprising a reciprocable pivoted head, a pair of clamping fingers fulcrumed on said head, a wedge-shaped block engaging said fingers, a spring connecting said fingers and pressing them against said block, mechanism for reciprocating said head and swinging it up and down on its pivot to disengage said fingers from the cigar at delivery position and move them to a position astride a cigar at band-applying position, mechanism for actuating said block to cause said fingers to clamp the cigar and carry it away from band-applying position in an arcuate path to delivery position and release it in delivery position, and a pusher on said head arranged to engage and further advance the cigar previously deposited in delivery position by said clamping fingers.

18. Means for clamping a cigar and depositing it in band-applying position, comprising a reciprocable head, a pair of clamping fingers fulcrumed on said head, a wedge-shaped block engaging said fingers, a spring connecting said fingers and pressing them against said block, and mechanism for actuating said block to cause said fingers to clamp a cigar and transfer it to band-applying position and release it in said position.

JOSEPH A. NEUMAIR.
